UNITED STATES PATENT OFFICE.

WILLIAM SUMTER BLACK, OF NORWALK, CALIFORNIA.

PUMPING DEVICE.

Application filed February 2, 1927. Serial No. 165,338.

This invention relates to deep well apparatus, oil, artesian or the like, and it is an object of my invention to provide a device attachable to the walking beam of an oil well pumping apparatus, and which will insure at all times that a vertical, even stroke is applied to the sucker-rod.

A second object of my invention is to provide a device which may be attached to any walking beam, which is easy to manufacture, is not likely to get out of order, and which is well adapted to perform the services required of it.

With the foregoing and other objects in view which will be made manifest in the following detailed description and specifically pointed out in the appended claims, reference is had to the accompanying drawings for an illustrative embodiment of the invention, 20 wherein:

Figure 1 is a side elevation showing a walking beam having my improved pumping device attached thereto, showing the same in assembled relation and in actual operation.

Figure 2 is a plan view of the showing in Figure 1.

Figure 3 is a view of a portion of my device, and

Figure 4 is an end view of the illustration 30 shown in Figure 3.

Referring to the accompanying drawings wherein similar reference characters designate similar parts throughout, the reference numeral 1 designates as an entirety the supporting structure of a walking beam in a deep well oil apparatus. This walking beam is designated at 2. A suitable bull wheel is indicated at 3 having a supporting structure 4 and a crank arm 5, 35 to which arm is pivoted, as at 6, the conventional type of pitman 7. A sucker rod is indicated at 8 and the oil well casing is shown in part at 9. These parts thus far referred to are conventional in form and no claim whatsoever is made as to their novelty. My preferred pumping device is used in connection with these parts and comprises a skeleton frame work designated as an entirety at 10. This frame work is formed of heavy durable material, such as steel or the like, and comprises the frames 11 and 12 respectively, which 40 frames are in spaced parallel relationship and are preferably identical in construction when the nature of the walking beam and supporting structure permits of the same. Each of these frames 11 and 12 comprises ra-

dial bars 13, 14, 15 and 16, respectively, which radial bars are connected at their outer end by a pair of arcuate rods 30 and 31. These arcuate rods are provided with spacing bars 60 32 which rigidly hold the same in spaced parallel relation. A plurality of rollers (in this case 6 are shown) are pivotally supported between the two radial arcuate bars. The rollers are arranged in vertical alignment and 65 have their centers of rotation arranged upon an arc having a center curvature coincident with the center of oscillation of the walking beam. The frames 11 and 12 may be secured to the walking beam in any desired manner. 70 Bolts or the like may be passed through them and through the walking beam or each frame may be separately nailed to the side of the walking beam. This frame work will adapt 75 itself to various types of walking beams and minor details in the construction of the same may be resorted to in order to enable the same to adequately fit the needs of each particular type of walking beam employed.

A curved track 35 extends from a point 80 adjacent the pivoted point of the walking beam outwardly and downwardly to a point substantially below the outer end of the walking beam. This curved track may be fastened by means of the braces 36, 37 and 38, 85 to the frame work or supporting structure of the walking beam or to convenient stationary objects located near by. No particular claim is made to the bracing structure of this curved track as it is only necessary that the same be 90 rigidly supported in its proper position with respect to the walking beam and the remainder of the oil well apparatus.

The upper radial links 16 are provided with enlargements or widened portions 40 between 95 which portions is pivoted a suitable pulley 41 or the like and this pulley is adapted to have extend over the same a cable 42, on one end of which there is provided a clamp 43 for attachment to the arcuate track 35 and 100 on the other end of the same means are provided for attachment to the upper end of the sucker rod. The clamp 43 is adapted to have its position along the arcuate track 35 varied so that a different depth of stroke may be imparted to the sucker rod without varying the stroke of the walking beam.

A suitable plate 45 is attached to the upper end of the sucker rod and is held in place by the nut 46. This plate is larger in cross section than the upper end of the casing 9. A second plate 47 is attached to the casing at 110

a point below its upper end and a heavy coiled spring 50 is disposed around the casing and centered thereby, extending a slight distance above the top of the casing. Should at any time during the operation of the device the cable or flexible member 42 break, due to wear or excess tensile stress, the plate 45 will be caught upon the coiled spring 50 and the entire sucker rod will be prevented from dropping within the well.

The stroke of the sucker rod may be varied by adjusting the position of the clamp 43 upon the track 35. It will be noted that the upper end of the track 35 is very close to the pivot point of the walking beam, while the lower end of the track is almost vertically beneath the pulley 41. If the clamp 43 is fastened to the track near its upper end, the portion of the cable between the pulley 41 and the clamp will be practically parallel to the walking beam. Consequently, during the oscillation of the walking beam, this portion of the cable will merely oscillate with the walking beam and the stroke imparted to the sucker rod will be equal in length to the vertical distance through which the pulley 41 passes. By shifting the clamp 43 to the bottom of the arcuate track, the portion of the cable between the pulley 41 and the clamp 43 will be practically perpendicular to the walking beam so that as the end of the walking beam having the pulley 41 rises, it will cause the sucker rod to be lifted twice as high as the pulley 41 will be lifted. In this manner the length of stroke of the sucker rod can be varied some distance equal to the vertical distance through which the pulley 41 passes to a stroke which is twice this amount. Any intermediate length can be obtained by adjusting the clamp 43 along the intermediate portions of the track 35, and if desired, the track can be calibrated for various lengths of stroke. As the rollers have their centers of rotation on an arc having a center curvature coincident with the center of oscillation of the walking beam, one roller will always be in engagement with that portion of the cable which is between the pulley 41 and the sucker rod and vertically above the sucker rod so that the portion of the cable which is disengaged and below the mentioned roller will almost hang vertically in alignment with the sucker rod. In this manner no lateral thrusts will be imparted to the sucker rod due to the swinging of the walking beam.

I do not desire to limit myself to the exact arrangement of parts clearly illustrated in Fig. 1 of the drawings, as I contemplate changing the design of my frame work to adapt itself to various types of walking beams. Although it will at all times be necessary to provide the arcuate rods 30 in such a position that they will perform the function of holding the sucker rod in a vertical position, I contemplate employing various

means for thus holding the same in position, I may dispense entirely with the radial rods 13, 14, 15 and 16, and employ in their place other braces attachable to points more remote on the walking beam. I may, should I so desire, provide additional braces for the arcuate track 35.

Various changes may be made in the details of construction by those skilled in the art without departing from the spirit of my invention, as claimed.

I claim:

1. A pumping device for oil wells comprising a pair of frames having an arcuate contour, said frames having radial arms attachable to a walking beam, pulleys on said arcuate contour, a drum on a pair of said arcuate rods, a cord extending over said drum and resting on said pulleys, said cord having one end attached to a sucker rod and means for attaching the other end of said cord at different positions with respect to said walking beam.

2. A pumping device for oil wells comprising a pair of frames, a drum mounted between said frames and having a flexible member inserted thereover, pulleys mounted between said frames, said flexible member being slidable on said pulleys, one end of said flexible member being attached to a sucker rod and the other end of said flexible member having a clamp thereon, a stationary arcuate track and means for attaching said clamp to said track adjustably.

3. The combination with a walking beam having a support of a pumping device, said pumping device comprising a pair of spaced arcuate rods rigidly attached to said walking beam, pulleys extending between said rods, a drum operatively mounted on the walking beam adjacent said pulleys, a flexible member extending over said drum and sliding on said pulleys, an arcuate track attached to the support for said walking beam, said flexible member being attached at one end to a sucker rod, the other end of said cord being provided with a clamp adjustably mounted on said track.

4. The combination with a walking beam having a support of a pumping device, said pumping device comprising a pair of arms, a pair of arcuate rods attached to said arms, said rods having mounted therebetween a plurality of pulleys, a drum attached operatively to the walking beam, a cord extending over said drum having one end attached to a sucker rod and means for attaching the other end of said cord to stationary points whereby the stroke of said sucker rod may be varied.

5. A pumping device for wells including a walking beam, a pulley mounted upon the walking beam, flexible means adapted to be connected to a sucker rod and extended over the pulley to an adjacent object, and means permitting variation of the position of the

portion of the flexible means between the pulley and the object with respect to the vertical, so as to vary the length of stroke imparted to the sucker rod.

5 6. A pumping device for wells comprising a walking beam, a pulley mounted for rotation upon the walking beam, a guide mounted adjacent the walking beam, a flexible element adapted to suspend a sucker rod extending 10 over the pulley, and means connecting the flexible element to the guide permitting the flexible element to be connected at various points along the guide so as to vary the position of that portion of the flexible element 15 between the pulley and guide with respect to the vertical and thus vary the length of the stroke imparted to the sucker rod.

7. A pumping device for wells including a walking beam, a pulley mounted upon the 20 walking beam, flexible means adapted to be connected to a sucker rod and extended over the pulley and secured to an adjacent object,

and means whereby the portion of the flexible means between the pulley and object may have its position varied so as to vary the angle 25 which the mentioned portion of the flexible element forms with the walking beam in any given position and thus vary the length of stroke of the sucker rod.

8. A pumping device for wells including a 30 walking beam, a pulley mounted upon the walking beam, flexible means adapted to be connected to a sucker rod having a first portion extending from the sucker rod to the pulley, and a second portion extending from 35 over the pulley to an adjacent object, and means for varying the position of at least a part of the second portion of the flexible means with respect to the vertical so as to vary the length of the stroke imparted to the sucker 40 rod.

In testimony whereof I have signed my name to this specification.

W. SUMTER BLACK.
